H. A. ADAMS,
RAZOR STROPPING DEVICE,
APPLICATION FILED MAY 11, 1917.

1,301,801.

Patented Apr. 29, 1919.

UNITED STATES PATENT OFFICE.

HARRY ALEXANDER ADAMS, OF NEW YORK, N. Y., ASSIGNOR TO SERVICEABLE INVENTIONS CORPORATION, OF NEW YORK, N. Y., A CORPORATION OF NEW YORK.

RAZOR-STROPPING DEVICE.

1,301,801.

Specification of Letters Patent. Patented Apr. 29, 1919.

Application filed May 11, 1917. Serial No. 167,917.

To all whom it may concern:

Be it known that I, HARRY ALEXANDER ADAMS, a citizen of the United States, and resident of the borough of Manhattan, city, county, and State of New York, have invented certain new and useful Improvements in Razor-Stropping Devices, of which the following is a specification.

The principal advantages of the invention are its simplicity, the fact that a number of razor blades may be contained in the holder, and the interchangeable and removable hone all of which combine to produce an efficient device for the purpose that will be described in the specification which follows.

The following is what I consider a good means of carrying out my invention and the accompanying drawing should be referred to for a complete understanding of the specification which follows.

In the drawing:—

Figure 1 shows my device in operation.

Fig. 2 shows the device open.

Similar reference numerals indicate like parts in all of the figures where they appear.

My device primarily consists of what may be termed a book, although the book consists only of 2 covers 1 and 2, hinged together about midlength by a suitable strap or hinge 3. The book may be constructed of any suitable material, and in my experiments I have constructed my book of stiff card board, covering the interior with artificial or natural leather, and the exterior with paper or celluloid or any other suitable material.

In the leather portion which is attached to the interior of the covers I provide a plurality of pockets or slits 5, 6 and 7 in the cover 1, and 8, 9 and 10 in the cover 2. These slits or pockets may be of any length, but those that I have shown are adapted to receive razor blades. On the interior of the cover 1, and adjacent to the slits 5, 6 and 7

45 I place the word "sharp" indicating that in these pockets sharp or unused blades are to be found therein, and on the other cover and adjacent to the pockets 8, 9 and 10 the word "dull" has an obvious significance.

50 On each cover and upon the inner side thereof and arranged adjacent to one end, I attach a piece of leather or canvas or other suitable material, and these two opposed

leather or canvas strips produce the stropping member.

Entered into suitable pockets or slits 11 and 12, at the opposite end and upon the interior of each of the cover members 1 and 2, I arrange pieces of canvas or other material upon which a suitable rouge or abrasive is placed, and these two opposed rouge carrying members comprise the honing means.

Each of the hone members 13 and 14 has rouge on both of its sides, and their attachment by tongues 15 and 16 into the slits or pockets 11 and 12 allows the hone members to be removed to be turned over so that the opposite sides may be used or other hone members substituted.

I provide a strap 17 and snap fastener 18, 19 for holding my book closed.

The operation of the device is as follows:

The book is opened, a razor blade removed and placed upon one of the hone members 13 or 14, the book is then closed with the razor blade 20 projecting beyond the end of the book as shown in Fig. 1. Then the razor blade is passed backward and forward across and between the hone members 13 and 14, one of which is, by the closing of the book, caused to impinge and bear upon the opposite surface of the razor blade.

When the honing is completed the razor blade is removed and inserted into the opposite end of the book, and between the stropping surfaces and a few movements of the blade between the strops 21 and 22 will complete the operation of honing and stropping the razor blade for use. After the 90 blade is used it may be returned to the pocket from which it was received or to a pocket in the opposite side of the book.

I have found that an ordinary amount of skill will allow an operator or user to produce upon the razor blade a very satisfactory edge.

My device may be used with a razor blade of any type, size or design.

The size of the device and the parts thereon may be changed at will. I may add additional pages to the book with added advantages and functions. The device may be made cheaply and when advertising is placed on the covers the device has an added 105 value.

The number of pockets and the size thereof may be changed at will, or I may subdivide the pockets for the reception of smaller blades.

5 Any other modifications may be made within the scope of the appended claims without departing from the principle or sacrificing the advantages of the invention.

Having carefully and fully described my 10 invention what I claim and desire to secure by Letters Patent is.

A book for holding safety razor blades 15 and sharpening means therefor comprising a pair of oblong covers having in their inner faces a plurality of longitudinal slits for holding blades, and a plurality of transverse

slits, a pair of opposed removable transverse honing members, each at one and the same end of the respective covers and each having a projection fitting a corresponding transverse slit, opposed stropping members at the opposite ends of the covers on the inner face thereof, and a flexible hinge connecting the covers and retaining the hone and strop members opposed in pairs.

20 Signed at New York city, county and State of New York this 30 day of April, 1917.

HARRY ALEXANDER ADAMS.
